[57] CLAIM

The ornamental design for a lifting tool for the collection of pine cones and the like, as shown and described.

DESCRIPTION

FIG. 1 is a right side elevational view of a lifting tool for the collection of pine cones and the like showing my new design, the left side being a mirror image of that shown and the handle being shown broken away to indicate indeterminate length;

FIG. 2 is a top plan view thereof;

FIG. 3 is a bottom plan view thereof;

FIG. 4 is a rear elevational view thereof; and

FIG. 5 is a front elevational view thereof.
A portion of the handle is omitted from FIGS. 2-5 for clarity of illustration.
